PAY-OFF REEL

John L. Losinski and John E. Schwermer,
Duluth, Minn.

Application April 6, 1949, Serial No. 85,848

5 Claims. (Cl. 242—84)

1

This invention relates to improvements in pay-off reels for feeding flexible material in coil form, such as wire, rod or the like, to various processing machines.

An object of the invention is to provide improved pay-off reels which accommodate a coil of flexible material for feeding and at least one reserve coil ready to be shifted to the feeding position so that feeding from the reel can be continuous.

A further object of the invention is to provide pay-off reels which accommodate reserve coils in addition to coils for feeding and which have improved devices for supporting the reserve coils and for shifting such coils to the feeding position.

A further object of the invention is to provide improved devices for supporting reserve coils in pay-off reels in which the reserve coils rotate with the feeding coils, thereby enabling the ends of the reserve and feeding coils to be joined for continuous feeding without stopping the reel.

A further object of the invention is to provide improved devices which support reserve coils in pay-off reels and which can be constructed by the addition of a few relatively simple parts to standard, single coil pay-off reels.

In accomplishing these and other objects of the invention, we have provided improved details of structure, a preferred form of which is shown in the accompanying drawings, in which:

Figure 1 is a top plan view of a pay-off reel which is equipped with an improved reserve coil supporting device embodying features of the present invention;

Figure 2 is a side elevational view of the reel;

Figure 3 is a side elevational view at right angles to the view of Figure 2 looking in the direction of the arrow 3 on Figure 2;

Figure 4 is a vertical sectional view taken substantially on line IV—IV of Figure 3; and

Figure 5 is a horizontal sectional view taken substantially on line V—V of Figure 4.

In the drawings there is shown a pay-off reel which comprises the usual stationary support and rotatable framework. The support includes a base 10 and an upright spindle 12. The framework includes a platform 13, inner and outer cages 14 and 15 fixed to said platform, and top and bottom bearings 16 and 17 fixed to the inner cage and platform respectively. These bearings are rotatably received on spindle 12. The reel is shown equipped with a wood brake bar 19 which is clamped rather loosely to the spindle and engages the inner cage to rotate therewith for preventing over-reeling and backlash. The platform

2

carries a coil S of flexible material, such as wire, rod or the like, which is positioned for feeding. The framework rotates relatively slowly, the rotative force being applied to the flexible material externally of the reel. The structure and operation thus far described are fairly typical of pay-off reels and hence are not described in greater detail. Also it is apparent that this structure may be altered considerably without affecting the reserve coil supporting device of the present invention.

In accordance with the present invention, the framework of the reel carries a pair of horizontal bearing sleeves 20 and 20a, which preferably are welded to diametrically opposed sides of inner cage 14. A pair of carriers 21 and 21a have axles 22 which are pivotally received in the respective sleeves. Each of said carriers is of U-shape in plan and has arms 23 which extend outside the framework and a bight 24 which extends inside the framework and is offset downwardly from the arms. Axle 22 is joined to each carrier at the bend between the arms and the bight. The carriers have two positions which are shown in full and in dot-dash lines in Figure 2 and are the coil supporting and coil releasing positions respectively. The carriers are balanced so that they normally gravitate to their coil supporting positions, in which their arms 23 are substantially horizontal and can support a reserve coil R.

A trip mechanism holds the carriers in their coil supporting positions against the weight of a reserve coil. This mechanism includes a sleeve 25 which is rotatably supported on spindle 12 and has laterally extending wings 26 and 26a which abut bights 24 of the carriers. An operating handle 27 is welded to sleeve 25 or to one of its wings. Normally the sleeve, wings and handle rotate with the framework, but they can be rotated manually relative to the spindle and framework. Such rotation frees wings 26 and 26a from the carrier bights. The weight of the reserve coil then pivots the arms to their coil releasing position in which the reserve coil drops to platform 13 into feeding position. When the carriers are free of the weight of the reserve coil, they gravitate back to their coil supporting positions and the trip mechanism is returned manually to the position in which its wings support the carriers. The device then is ready to receive another reserve coil.

From the foregoing description it is seen that pay-off reels which are equipped with reserve coil supporting devices of the present invention can carry a reserve coil above the coil that is

feeding and that both coils rotate at the same speed. Inasmuch as the rate of rotation is relatively slow, the leading end of the reserve coil can be joined to the trailing end of the coil which is feeding without stopping the reel. When the coil which is feeding is exhausted, the reserve coil can be shifted quickly to the feeding position and the device reset to receive another reserve coil. Therefore such devices eliminate interruptions in feeding the coils and expedite whatever operation is performed on the coils. The device is constructed of simple parts which can be added readily to pay-off reels of many standard designs.

While we have shown and described only a single embodiment of the invention, it is apparent that modifications may arise. Therefore, we do not wish to be limited to the disclosure set forth but only by the scope of the appended claims.

We claim:

1. In a pay-off reel for feeding flexible material from coils comprising a stationary support and a framework mounted to rotate as a unit on said support and having means for supporting a coil for feeding, a device for supporting a reserve coil on said framework above said first named coil supporting means including carriers supported on said framework to rotate therewith and movable to coil supporting and coil releasing positions, said carriers being balanced to move normally to their coil supporting positions when free of a coil and to their coil releasing positions under the weight of a coil, and trip mechanism for holding said carriers in their coil supporting positions against the weight of a coil and being releasable from said carriers to enable the latter to move to their coil releasing positions to drop a coil supported thereon to said first named coil supporting means.

2. In a pay-off reel for feeding flexible material from coils comprising a stationary support and a framework mounted to rotate as a unit on said support and having a platform for supporting a coil for feeding, a device for supporting a reserve coil on said framework above said platform including a pair of carriers supported on said framework to rotate therewith and movable to coil supporting and coil releasing positions, said carriers being balanced to move normally to their coil supporting positions when free of a coil and to their coil releasing positions under the weight of a coil, and trip mechanism rotatably mounted on said stationary support and normally rotatable with said framework, said trip mechanism supporting said carriers in their coil supporting positions against the weight of a coil and being manually releasable from said carriers to enable the latter to move to their coil releasing positions to drop a coil supported thereon to said platform.

3. In a pay-off reel for feeding flexible material from coils comprising a stationary support and a framework rotatably mounted on said support and having a platform for supporting a coil for feeding, a device for supporting a reserve coil above said platform including a pair of U-shaped carriers supported on said framework to rotate therewith and having arms extending outside said framework and adapted to support a reserve coil and bights extending within said framework, said carriers having coil supporting and coil re-

leasing positions and being balanced to move normally to their coil supporting positions when free of a coil and to their coil releasing positions under the weight of a coil, and trip mechanism engageable with said bights for holding said carriers in their coil supporting positions against the weight of a coil and being releasable from said bights to enable said carriers to move to their coil releasing positions to drop a coil supported thereon to said platform.

4. In a pay-off reel for feeding flexible material from coils comprising a stationary support and a framework rotatably mounted on said support and having a platform for supporting a coil above said platform including a pair of U-shaped carriers supported on said framework to rotate therewith and having arms extending outside said framework and adapted to support a reserve coil and bights extending within said framework, said carriers having coil supporting and coil releasing positions and being balanced to move normally to their coil supporting positions when free of a coil and to their coil releasing positions under the weight of a coil, a sleeve rotatably mounted on said stationary support and normally rotatable with said framework, wings on said sleeve engageable with said bights for holding said carriers in their coil supporting positions, and means for rotating said sleeve manually relative to said framework for releasing said wings from said bights to enable said carriers to move to their coil releasing positions and drop a coil supported thereon to said platform.

5. In a pay-off reel for feeding flexible material from coils comprising a stationary base, an upright spindle fixed to said base, and a framework rotatably mounted on said spindle and having a platform adjacent its lower end for supporting a coil for feeding, a device for supporting a reserve coil above said platform including a pair of U-shaped carriers supported on said framework to rotate therewith and having arms extending outside said framework and adapted to support a reserve coil and bights extending within said framework, said carriers being movable on horizontal axes to coil supporting and coil releasing positions and being balanced to move normally to their coil supporting positions when free of a coil and to their coil releasing positions under the weight of a coil, a sleeve rotatably mounted on said spindle and normally rotatable with said framework, wings on said sleeve engageable with said bights for holding said carriers in their coil supporting positions, and means for rotating said sleeve manually relative to said framework for releasing said wings from said bights to enable said carriers to move to their coil releasing positions and drop a coil supported thereon to said platform.
